CLAIM

The ornamental design for outerwear as shown and described.

DESCRIPTION

FIG. 1 is a front left side perspective view of outerwear showing my new design;

FIG. 2 is a front view thereof; and,

FIG. 3 is a front right side perspective view thereof. The parallel even-length broken lines represent a zipper which forms no part of the claimed design. The remaining uneven-length broken lines represent portions of the outerwear that form no part of the claimed design.

1 Claim, 3 Drawing Sheets

FIG. 1

FIG. 3
